UNITED STATES PATENT OFFICE.

WILLIAM DE LAMATER, BURLINGAME, KANSAS, ASSIGNOR OF TWO-THIRDS
TO ANDREW ERWIN, OF SAME PLACE, AND WILLIAM C. EDWARDS, OF
TOPEKA, KANSAS.

EXPLOSION-PROTECTOR FOR SAFES.

SPECIFICATION forming part of Letters Patent No. 269,920, dated January 2, 1883.

Application filed February 20, 1882. (No model.)

To all whom it may concern:

Be it known that I, WM. DE LAMATER, a citizen of the United States, residing at Burlingame, in the county of Osage and State of 5 Kansas, have invented a new and useful Explosion-Foil for Burglar-Proof Safes, of which the following is a specification.

My invention relates to a certain combination and arrangement of a plug fitted into the 10 door or wall of a safe with a locking device, which effectually prevents the plug from being withdrawn on the outside, but which is automatically unlocked whenever an explosion occurs within the safe, releasing the plug, which 15 is at once driven out of the door or wall, and so provides a vent which instantly relieves the door and walls from the pressure generated by the explosion and prevents the safe from being blown open.

20 Figure 1 shows my invention complete in place and ready for operation. Fig. 2 shows a longitudinal section of the plug or bolt, which constitutes the prime feature of the invention. Fig. 3 shows the funnel-mouthed locking and 25 unlocking cylinder. Fig. 4 shows the bolt-locking tongue with its unlocking-levers, and Fig. 5 shows the complementary unlocking-cartridge and firing coil or cage. Figs. 2, 3, 4, and 5 are constructed on a scale of one-half 30 inch to the inch.

Similar letters refer to similar parts throughout the several views.

The plug or bolt A is of iron or steel, with a double head, a and a', a socket, b, sunk from 35 its inner end, and an annular groove, c, near the same end. When the plug is in place the outward shoulder of this groove c should be flush with the inner surface of the door or wall of the safe, while the plug itself should extend just far enough into the safe to afford ample material for strength between its end and the inner shoulder of the groove. The head a of the plug should be just flush with the outer surface of the door or wall of the safe, and may 40 be so covered in painting as to effectually conceal its location.

The locking-tongue B should be made of steel, and should be securely attached to the inner side of the door or wall of the safe by a

50 pivot, x, that will permit it, with its unlocking-levers d, to oscillate freely in a plane parallel with the surface to which it is attached. The oscillating joint should be at such a distance from the plug A as to permit the locking-tongue to fit into and fill that portion of the 55 groove c opposed to it. By this means the plug is securely locked into the door or wall of the safe, and can neither be driven in nor withdrawn.

55 The funnel-mouthed locking and unlocking cylinder C is made of brass and closed at its small end. It may be uniform in diameter or gradually reduced in size from the termination of its funnel portion. This funnel portion must be so constructed that when the cylinder is 60 fully inserted into the socket b of the plug the extreme funnel circumference will just coincide with the outer circumference of the inner end of the plug and pass out with the plug when it is withdrawn from the door or wall of 65 the safe. When in position in the socket b the funnel of the cylinder must stand off from the end of the plug just far enough so that the short pin e jutting from the extreme funnel circumference may pass into the eye e' of the 70 pendent U-shaped stout wire f, whose ends are firmly secured to the locking-tongue B and one of the unlocking-levers d. By this means 75 the locking-tongue B is prevented from oscillating out of the groove c, or is locked to its place, while it is unlocked as soon as the cylinder C is forced back into the socket b and the pin e withdrawn from the eye e' of the pendent wire f.

80 The unlocking-cartridges D are made of brass or of common cartridge-case material, and have 85 their closed ends next the firing coils or cages E punctured to communicate a spark from the flashing-powder of the cages E to the powder of the cartridges. These cartridges are secured to the inner side of the door or wall of the safe by the bands g. The firing-coils E are 90 of coarse brass wire closely coiled in cone shape for conveniently closing one end. These cages are fully charged with powder, and are 95 secured to the inner surface of the door or wall of the safe by any convenient method, their open ends resting upon the closed ends of the

cartridges, while both the cartridges must be so located as to permit their open ends to rest upon the bracket offsets or seats *h* at the free ends of the levers *d*, the one cartridge facing 5 one side of one of the lever-seats and the other cartridge the opposite side of the other seat. Within each cartridge is compressed to about one-half its normal length a free spiral spring, 10 *i*, which rests between the charge of the cartridge and the bracket-seat of the lever.

When a safe is furnished with my invention constructed and arranged as now described and shown, any attempt to blow it open must be foiled, for the firing of the powder or the 15 explosion of any substance designed to blow the safe open will force the cylinder *C* into the socket *b* and release the tongue *B*, which will at once be oscillated from the groove *e* by the force of the spiral springs *i*, and the fired powder 20 of the cages *E* and cartridges *D* will drive out the plug *A* and instantly provide a vent, which will afford relief to the walls and bolts of the safe from the pressure generated by the explosion. The coils or cages *E*, with the explosive 25 of the cartridges *D*, which are fired by the charge introduced within the safe, are not essential to the successful working of the invention, but may be used when desired as accessories. When the cages *E* and cartridges *D* are 30 not charged with powder the discharge of any explosive within the safe will, as before, force

the cylinder *C* into the plug or bolt *A* and unlock the tongue *B*, which will then be oscillated from its groove in the bolt by the simple elasticity of the coiled springs within the cartridges *D*, and the bolt will consequently be driven out by the force of the explosion and afford relief to the walls of the safe. 35

I claim and desire to secure by Letters Patent—

1. For neutralizing the effect of discharging an explosive inside a bank or other money safe, a device consisting of a hollow plug or bolt, *A*, locked in place by the oscillating tongue *B* and cylinder *C*, with its pin *e* and pendent wire 45 *f*, and unlocked by the levers *d*, operated by the coiled springs within the cartridges *D*, constructed, combined, and operating substantially as hereinbefore described.

2. The plug or bolt *A*, constructed, arranged, 50 and operating as hereinbefore described, in combination with the locking-tongue *B*, the locking and unlocking cylinder *C*, the complementary unlocking-levers *d*, and spiral springs *i*, together with the cartridges *D* and firing-cages *E*, all constructed and operating substantially as and for the purpose hereinbefore described. 55

WM. DE LAMATER.
